Morris Schwartz
By G. L. Gragg Atty.

UNITED STATES PATENT OFFICE.

MORRIS SCHWARTZ, OF CHICAGO, ILLINOIS, ASSIGNOR OF ONE-HALF TO WINNIFRED B. PARISH, OF CHICAGO, ILLINOIS.

BUSHING STRUCTURE.

Application filed December 18, 1922. Serial No. 606,605.

To all whom it may concern:

Be it known that I, MORRIS SCHWARTZ, a citizen of the United States, residing at Chicago, in the county of Cook and State of Illinois, have invented a certain new and useful Improvement in Bushing Structures, of which the following is a full, clear, concise, and exact description.

My invention relates to apertured structures having bushings in the apertures thereof. The invention is of particular service in the construction of barrels, the bushing lining the barrel opening and its bore constituting the bung hole. The bushing may 15 be interiorly threaded to receive a threaded bung.

In carrying out my invention the hole in the barrel is margined by an annular rim and the annular bushing is generally U- 20 shape in cross section and receives said rim in the annular space between its walls. One rim of the bushing has lateral edge portions at different distances from the axis of the bushing and the barrel wall in the 25 region of the bung hole is formed with a pocket that surrounds the hole and which receives the exterior rim of the bushing. Said pocket has an outer wall extending longitudinally of the bushing and engaging the 30 lateral edge portions of the outer bushing rim whereby the bushing is locked from rotation with respect to the barrel wall which carries it.

The invention will be more fully explained 35 by reference to the accompanying drawing in which Fig. 1 is a view in elevation, with parts broken away, of a structure made in accordance with the preferred embodiment of the invention, this view being taken from 40 the outer side of the support that carries the bushing; Fig. 2 is a view taken from the inner side of the bushing support; Fig. 3 is a sectional view on line 3—3 of Fig. 1 with the bung shown in elevation; Fig. 4 is a per- 45 spective view illustrating the assembly of the bushing and its support; and Fig. 5 is a sectional view on line 5—5 of Fig. 1 but on a larger scale.

Like parts are indicated by similar char- 50 acters of reference throughout the different figures.

The support 1 may be a barrel end wall. It has a hole formed therethrough which is 55 margined by an annular rim 2. The bush- ing 3 is U-shape in cross section with the

sides of the U substantially parallel with the axis of the bushing to form a pocket extending longitudinally of the bushing receiving the aforesaid rim in the annular space between its walls. The exterior or outer rim 60 4 of the bushing is outwardly deflected and is preferably in the form of a polygonal flange whereby this bushing rim is provided with lateral edge portions at different distances from the axis of the bushing that 65 are engaged by an element to be specified to prevent the bushing from turning in its support.

The support 1 is formed with a pocket 5 in its body portion that receives the flange 70 4, this pocket having an outer wall 6 extending longitudinally of the bushing and engaging lateral edge portions of the flange 4 whereby the bushing is held from rotation with respect to the support. Said pocket surrounds and is spaced apart from the rim 2 and has an inner wall 7 which forms a shoulder 8 at the middle of the pocket bottom to form an inner annular recess upon the exterior of the pocket 80 bottom. The interior rim 9 of the bushing is originally positioned as illustrated in Fig. 5 by dotted lines in order that the rim 2 of the support may be inserted in this annular recess in the exterior of the pocket 85 bottom.

When the rim 2 has been inserted the interior bushing rim 9 is outwardly deflected over the base of rim 2 into engagement with the shoulder 8 sufficiently to overlie the polygonal flange 4 of the bushing that is received in the space between the pocket walls. The rims 4 and 9 of the U shaped bushing are in snug engagement with the portion of the support 1 surrounding the rim 2, 90 one rim of the bushing lapping the other and closely confining the portion of the support 1 interposed therebetween. The annular rim 2, the annular shoulder 8 and the annular portion of the support 1 intervening 95 between its portions 2 and 8 are together S-shaped in cross section, the bushing rims 4 and 9 engaging the annular intermediate part of this S-shaped portion, the rim 9 abutting against said shoulder. By this 100 construction a firm locking engagement is afforded between the bushing and its support, the joint being substantially fluid tight.

The bore of the bushing is desirably 105 threaded to receive the threaded bung 110

which has a flange 11. A sealing gasket 12 is interposed between the flange 11 on one side of the flange 9 and the bottom of the pocket 5 on the other side, this sealing gasket sealing the gap that might possibly exist between the flange 9 and the pocket 5 to intercept any fluid that might work its way between the support 1 and the bushing.

As the invention is embodied the bushing flange 4 is upon the inner side of the barrel and the hexagonal tool engaging end of the bung is upon the outside of the barrel. If it should happen that the bushing is somewhat loose in its assembly with the rim 2, the bung, in being tightened, will firmly lock the bushing flange 4 in the pocket 5.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. The combination with a support having a hole therethrough and having a rim portion margining said hole; of an annular bushing having rims thereon and having a portion U-shaped in cross section with a groove between the sides of the U and receiving said rim portion between its sides, the rims of said bushing engaging the portion of said support which surrounds the rim portion of the support, one of these bushing rims lapping the other, a side of said U-shaped bushing having portions at different distances from the axis of the bushing and engaging portions upon the support that are also at different distances from the axis of the bushing to hold the bushing from turning.

2. The combination with a support having a hole therethrough and having a rim portion margining said hole, said support having a part surrounding the hole and con-

tiguous to said rim and a shoulder between which and said rim said support part intervenes, said rim, shoulder and said intervening support part constituting a support portion S-shaped in cross section; of an annular bushing having rims thereon and having a portion U-shaped in cross section with a groove between the sides of the U and receiving said rim portion within the groove, one of the rims of the bushing lapping the other, these bushing rims snugly engaging the aforesaid intervening support part therebetween, the lapping rim of said bushing engaging the aforesaid shoulder, one of the bushing rims having edge portions at different distances from the axis of the bushing and the support having portions engaging these edge portions of the latter bushing rim to prevent the bushing from turning.

3. The combination with a support having a hole therethrough and having a rim portion margining said hole, said support having a part surrounding the hole and contiguous to said rim and a shoulder between which and said rim said support part intervenes, said rim, shoulder and said intervening support part constituting a support portion S-shaped in cross section; of an annular bushing having rims thereon and having a portion U-shaped in cross section with a groove between the sides of the U and receiving said rim portions between its sides, one of the rims of the bushing lapping the other, these bushing rims snugly engaging the aforesaid intervening support part therebetween, one of the bushing rims having edge portions at different distances from the axis of the bushing and the support having portions engaging these edge portions of the latter bushing rim to prevent the bushing from turning.

In witness whereof, I hereunto subscribe my name this 9th day of December A. D., 1922.

MORRIS SCHWARTZ.
